CLAIM

The ornamental design for a clip and claw assembly for an inside-the-waistband firearm holster, as shown and described.

DESCRIPTION

FIG. 1 is a perspective view of a clip and claw assembly for an inside-the-waistband firearm holster showing an embodiment of our new design;

FIG. 2 is a front view of the clip and claw assembly for an inside-the-waistband firearm holster shown in FIG. 1;

FIG. 3 is a back view of the clip and claw assembly for an inside-the-waistband firearm holster shown in FIG. 1;

FIG. 4 is a right side view of the clip and claw assembly for an inside-the-waistband firearm holster shown in FIG. 1;

FIG. 5 is a left side view of the clip and claw assembly for an inside-the-waistband firearm holster shown in FIG. 1;

FIG. 6 is bottom view of the clip and claw assembly for an inside-the-waistband firearm holster shown in FIG. 1;

FIG. 7 is top view of the clip and claw assembly for an inside-the-waistband firearm holster shown in FIG. 1;

FIG. 8 is a perspective view of the clip and claw assembly for an inside-the-waistband firearm holster of FIG. 1 mounted to a firearm holster;

FIG. 9 is a front view of the clip and claw assembly for an inside-the-waistband firearm holster shown in FIG. 1 mounted to a firearm holster;

FIG. 10 is a back view of the clip and claw assembly for an inside-the-waistband firearm holster shown in FIG. 1 mounted to a firearm holster;

FIG. 11 is a right side view of the clip and claw assembly for an inside-the-waistband firearm holster shown in FIG. 1 mounted to a firearm holster;

FIG. 12 is a left side view of the clip and claw assembly for an inside-the-waistband firearm holster shown in FIG. 1 mounted to a firearm holster;

FIG. 13 is bottom view of the clip and claw assembly for an inside-the-waistband firearm holster shown in FIG. 1 mounted to a firearm holster; and,

FIG. 14 is top view of the clip and claw assembly for an inside-the-waistband firearm holster shown in FIG. 1 mounted to a firearm holster.

The broken lines in FIGS. 1-14 illustrate unclaimed subject matter and do not form any part of the claimed design.
